10 Claims. (Cl. 204—86)

This invention is a continuation in part of application SN. 45,669, now U.S. Patent 3,109,795, issued Nov. 5, 1963.

This invention relates to an electrolytic cell and more particularly to a diaphragm in an electrolytic cell.

In some electrolytic cells, a reactive material present in the cell reacts with one of the products being produced at either the anode or the cathode of the cell to produce an end product. It has been found that in certain cells of this type a shut-down of the cell for cleaning of the diaphragm becomes desirable when the reactive material included in the cell wets or builds up on the diaphragm. Build-up of the reactive material on the diaphragm, if it does not cause the cell to malfunction, causes at least a decrease in the efficiency of the cell and a corresponding decrease in the yield of the desired end product. The build-up of the reactive material on the diaphragm may also cause an increase in the electrical power needed for operation of the cell, thus increasing the cost of operating the cell and adding to the electrical load of the installation.

Build-up on the diaphragm has been found to occur in an electrolytic phosphine producing cell. In such a cell, phosphorus is the material which wets the diaphragm and reacts with the electrolytic product formed at the cathode. Such build-up of a wetting material, phosphorus, may be prevented by means of the present invention.

It is an object of this invention to provide an improved electrolytic cell.

Another object of the invention is to prevent the wetting of a diaphragm by a reactive material contained within an electrolytic cell, thereby increasing cell life and efficiency.

Another object is to protect a diaphragm in an electrolytic cell which is wetted by a reactive material contained within the cell.

A further object is to inhibit wetting of a diaphragm by molten phosphorus in an electrolytic cell producing phosphine.

The invention has particular application to uses in which the reactive material is phosphorus and a product of the cell is phosphine. Another aspect of the invention which is of importance is the structure of the covered or sheathed diaphragm and the materials thereof.

In accordance with this invention, it has been found that an electrolytic cell will be of increased efficiency when it comprises anodic and cathodic electrodes, a diaphragm separating anode and cathode, an electrolyte in contact with the electrodes and the diaphragm, from which electrolyte a product of electrolysis is formed at an electrode when an electric current flows between the electrodes through the electrolyte, and a reactive material in the cell, which material is reactive with a product of electrolysis produced at an electrode, the diaphragm having a surface thereof facing the reactive material which is such that electrolyte ions may pass through it and is of a material which is not wetted by the reactive material.

Other objects and aspects of the invention will be apparent from the following description, taken with the drawing illustrative of the embodiment of the invention, in which drawing FIGURE 1 is a central vertical sectional view of apparatus of this invention along 1—1, and FIGURE 2 is a horizontal sectional view along 2—2.

Cell vessel 10, contains anode compartment 12, anode

14, cathode compartment 16, and cathode 18. A porous or permeable diaphragm 20 separates anode and cathode compartments and separates the electrolyte into anolyte 17 and catholyte 19 sections. In the cathode compartment 16 is a reactive material 24, e.g., phosphorus, in liquid state. Diaphragm 20 is covered, coated, or protected in such a manner that the side thereof facing the reactive material, where it may otherwise contact that material, is coated with a coating, cover or sheath 22 against which the reactive material then does not adhere or wet the coating, which action is evidenced by convex meniscus 21. Ports 26 and 28 permit the addition and removal of anolyte from the anode section 12. Ports 30 and 32 permit the addition and removal of catholyte from the cathode section 16. Port 34 permits the addition and removal of the reactive material from cathode section 16. Sufficient reactive material 24 is added to the cathode compartment 16 to contact the portion or edge of cathode 18, permitting contact of the reactive material with a greater surface of the cathode by a wetting action. Anolyte gas discharge port 36 is provided in the top of the anode section to remove analyte gas from the electrolytic cell. Catholytic gas discharge port 38 is provided on the top of the cathode section 16 to remove catholyte gas. 25 Gas-liquid interfaces are indicated at 15.

Electrolyzing current to the electrodes is transmitted by anode electrical connector 40 and cathode electrical connector 42 joining the anode and cathode to the positive and negative poles, respectively, of a source of direct current 44.

If desired, a heating or cooling means, such as a constant temperature bath, not shown, may be employed to maintain the cell at or near a desired temperature.

Cell vessel 10 may be constructed of a material capable of resisting corrosion by the electrolyte and other materials employed in the cell. Typical examples of suitable materials of construction of cell vessel 10 include glass, glazed ceramic, tantalum, titanium, hard rubber, polyethylene, polyurethane, rigid materials coated with phenol-formaldehyde resin, and the like.

Diaphragm 20 which separates the anode section 12 from the cathode section 16 may be semipermeable or permeable material resistant to the cell contents and capable of maintaining the anode and cathode gases separate. Typical examples of suitable materials for use as a diaphragm include: porous alundum, porous porcelain, resin impregnated wool felt, and various other separators of the types which may be normally employed in lead storage batteries.

Cover, coating or surface 22 is a material which does not become wetted by the reactive material. Such lack of wetting effect is indicated by formation of a convex meniscus when the surface is in contact with a reactive material contained in the cell. The surface, in essence, prevents the reactive material from wetting the diaphragm. In a preferred embodiment of this invention, glass fabric is the material which is non-wettable by phosphorous. Examples of other non-wettable materials suitable for the practice of this invention are vinylidene polymers, polypropylene, polyurethane, chlorinated polyether, acrylonitrile resins, polyethylene, fluorinated hydrocarbon resins, polyester resins, polyvinyl chloride resins, graphite, phenolformaldehyde resins, natural gum rubber and chloroprene resins. It is preferred that the above resins be fabrics thereof, but it is to be understood that the resins themselves in their thermosetting or thermoplastic forms may also be utilized in the invention in accordance with the description herein. These sheathing materials also should be permeable, non-resistance to electrochemical flow and stable in the electrolyte media which may be utilized.

The cover material may be applied to the diaphragm by any suitable method, as by spraying, fusing, adhering, wrapping about the diaphragm, mechanically fastening, depositing, and integrally forming with the diaphragm. It is preferred, however, to form a fabric material into the shape of the diaphragm, but slightly larger and then to insert the diaphragm into the preformed sheath. Alternatively, one may wrap the fabric around the diaphragm and fasten it so that it will remain in place. The diaphragm is then placed into and connected to the cell vessel 10. It is to be understood that one or both sides of the diaphragm may be coated, usually depending on which surface or surfaces may come into contact with the reactive material.

Solid materials having a hydrogen over-voltage, as normally measured in the absence of the reactive material, exceeding the hydrogen over-voltage of smooth platinum may be employed as the cathode. Typical cathodic materials include lead, amalgamated lead, cadmium, tin, aluminum, nickel, alloys of nickel, such as Mumetal (an alloy containing 77.2 percent nickel, 4.8 percent copper, 1.5 percent chromium, and 14.9 percent iron), Monel, copper, silver, bismuth, and alloys thereof. For example, lead-tin, lead-bismuth, and tin-bismuth alloys may be employed. Various shapes of cathodes may be employed, e.g., the cathode may be cylindrical as illustrated, or may be of plate or other shape. Mats of metallic wool and porous metallic sheaths may also be employed, if desired. Essentially the reactive material will wet such materials and rise to cover the cathode surface thinly, promoting reaction with the product of electrolysis generated at the cathode surface. Suitable anode materials include lead, platinum, lead peroxide, graphite and other materials of construction capable of conducting current and resisting corrosion under the conditions of electrolysis employed.

The electrolyte may be a salt or other organic or inorganic electrolyte which is itself nonreactive with the reactive material utilized and which is capable of forming a product, e.g., hydrogen gas or ion, under electrolytic conditions employed which will react with the reactive material. Typical examples of suitable compounds in aqueous solution which may be employed as the electrolyte include hydrochloric acid, sodium chloride, lithium chloride, potassium chloride, sodium sulfate, potassium sulfate, monosodium phosphate, disodium phosphate, acetic acid, ammonium hydroxide, phosphoric acid, sulfuric acid and mixtures thereof. The concentration of a compound in an aqueous electrolyte may vary from about 1 to about 95 percent, but is usually between about 5 and about 80 percent, preferably between about 10 and about 50 percent.

Improved results have been obtained when metallic ions are present in the electrolyte in small proportions. For example, suitable concentrations of metal ions may be between 0.01 percent and 5 percent by weight of electrolyte, however, between about 0.02 percent and 3 percent by weight of electrolyte may also be utilized. Preferably though between about 0.02 percent and 0.5 percent by weight of electrolyte may be utilized. Examples of metallic ions which may be utilized are antimony, bismuth, lead, tin, cadmium, mercury, silver, zinc, cobalt, calcium, barium, and mixtures thereof. The metal ions may be placed in the electrolyte by employing a consumable anode of the desired metal or metals, such as a lead anode, whereby the metal ions are formed in the electrolyte and transferred to the area adjacent to the cathode. Salts or other compounds of the metals such as chlorides, phosphates, acetates, and the like, also may be dissolved in the electrolyte if desired. In another embodiment, finely divided metal in elemental form is added to the electrolyte.

The diaphragm protected in the manner illustrated and described herein is preferably utilized in the electrolytic production of phosphine. In a cell utilized for such production, the temperature of the catholyte and anolyte

should be maintained above the melting point of phosphorus (about 44 degrees centigrade), and below the boiling point of the electrolyte. Temperatures between about 60 degrees centigrade and 110 degrees centigrade are satisfactory, but optimum yields of phosphine are obtained at temperatures between about 70 degrees centigrade and 100 degrees centigrade. When an electric current is passed through the cell, molten phosphorus on the surface of the cathode is consumed in the formation of a catholyte gas in the cathode section. The catholyte gas is predominantly phosphine, but contains some hydrogen. The anolyte gas depends on the over-voltages of the anions in the anolyte, with reference to the anode material. Thus, for example, the anolyte gas predominates in oxygen if sulfuric acid or phosphoric acid is used with a platinum anode, whereas for the same anode, chlorine predominates if hydrochloric acid is used as anolyte. Thus, the coproduction of anodic oxidation products may be carried out in the anode compartment of the cell of this invention without departing from the spirit of the invention.

As phosphorus is consumed on the surface of the cathode to yield phosphine, additional phosphorus wets the cathode and passes from the molten pool to the vertical cathodic surface. The current density on the cathode may be controlled so that the phosphorus is consumed at a rate at which it is replenished on the cathode surface from the molten pool of phosphorus. The cathode current density may be set by the operator and is dependent on which density gives the best results, the cell design and the construction of the cathode. For example, when a porous lead cathode is employed, and the height of the phosphorus layer on the cathode is about 5½ inches, the optimum cathodic current density appears to be between about 6 and 12 amperes per square foot. However, other current densities consistent with the economic production of phosphine may be employed.

The phosphine containing gas produced at the cathode has a relatively high concentration of phosphine, usually more than 60 percent, and it may be as high as 90 percent phosphine by volume or higher. The catholyte gas is substantially free from other phosphorus hydrides.

In one embodiment of the invention, a lead plate is employed as the cathode, and a graphite rod is employed as the anode with an alundum diaphragm coated with glass fabric to keep the phosphorus from the diaphragm, separating the anode from the cathode. Under these conditions, it has been found that the operation of the cell is markedly improved as is further illustrated by the examples below.

In carrying out the process of the invention, it was observed that a wicking action occurred at the cathode prior to energizing the cell, that is, a thin layer of molten phosphorus formed on the outer surface of the vertical metallic cathode above the level of the molten pool of phosphorus before any current was impressed upon the system.

As soon as a current is caused to flow and is maintained the wicking action becomes more rapid. It was further observed that the rate of the wicking action was faster for some metals than others, and that the thickness of the phosphorus layer on the metal surfaces was thicker on some metals than on others. Further, in the utilization of the invented apparatus for phosphine production when phosphorus is the reactive material, it has been found that the non-wetting materials, sheathing the diaphragm prevents the diaphragm from building up a layer of phosphorus on its surface, which otherwise would cause a decrease in the efficiency of the cell. It is to be understood that a reactive material which produces a convex meniscus at the sheathing or coating of the diaphragm will not wet the diaphragm and thereby increase the efficiency of an electrolytic cell containing reactive material. Suitable reactive materials which may be utilized in the apparatus of the invention are sulfur, the alkali metals and their salts, e.g., potassium, sodium lithium, rubidium, cesium, sodium chloride, etc., alkaline earth metals, e.g., beryllium,

calcium, strontium, barium, as well as magnesium, germanium and lead.

The porosity or openings of the coating material may be between 0.5 micron and $\frac{1}{16}$ of an inch, as desired, to block the flow of reactive material through the protective coating of the diaphragm.

The following examples are presented to further illustrate the invention, without any intent of being limited thereby. All parts are by weight and all temperatures are in degrees Centigrade, unless otherwise specified.

Example 1

To an electrolytic cell containing a graphite anode and lead cathode were added 2,330 parts of 10 percent hydrogen chloride solution containing 1 gram per liter of lead chloride. A porous alundum diaphragm in a glass cloth sleeve with openings about $\frac{1}{64}$ of an inch, separated the anode and cathode so as to form anodic and cathodic compartments. 266 parts of phosphorus were added to the cathodic chamber. The cell was maintained at 95 degrees centigrade. An electric potential was applied to the electrodes to cause flow of a current of about 4.6 amperes. After about 102 days of continuous operation at these conditions to produce phosphine at the rate of 45 grams PH₃/day, various ingredients being added as required, inspection revealed no wetting of the diaphragm with phosphorus and no decrease in the operational efficiency of the cell as indicated by the fact that no change in applied voltage was required.

Example 2

Example 1 was repeated, except for the omission of the glass fabric sleeve. The cell was operated for about 66 days. The voltage during this period had to be increased from 4.2 to 5.3 volts. At the time of shut down, 70 percent of the porous diaphragm area was coated with phosphorus and was blocked by it.

Examples 3 to 14

These examples illustrate the various nonwettable materials which may be utilized in place of glass cloth to sheath or cover the diaphragm of the electrolytic cell of Example 1, and thereby to increase the efficiency of the cell by preventing the deposition of a reactive material on its surface to block openings therein. Elemental phosphorus under concentrated hydrochloric acid was heated to cell temperature, between about 70 and 80 degrees centigrade. The following fabrics were then tested:

TABLE I

	Fabric	Nonwettable by Phosphorus	Wettable by Phosphorus
3.	Polypropylene	X	
4.	Polyurethane	X	
5.	Chlorinated polyether (Pentom (R))	X	
6.	Acrylonitrile resin (Orlon (R))	X	
7.	Polyethylene	X	
8.	Fluorinated hydrocarbon (Fluorone (R))	X	
9.	Polyester (Dacron (R))	X	
10.	Polyvinyl chloride (Tygon (R))	X	
11.	Graphite (rod and fabric)	X	
12.	Phenolformaldehyde resins	X	
13.	Natural gum rubber	X	
14.	Polymer of chloroprene (Neoprene (R))	X	

It will be recognized by those skilled in the art that various modifications within the invention are possible, and will be obvious to one of skill in the art, with this specification before him. Therefore, this invention is not to be limited except as defined by the appended claims.

What is claimed is:

1. A process for producing chemicals which comprises contacting anodic and cathodic electrodes with an electrolyte, the lower portion of an electrode being in

contact with a material reactive with a product of electrolysis produced there, said reactive material being selected from the group consisting of phosphorus, sulfur, alkali metals, alkaline earth metals, magnesium, germanium, and lead, maintaining a thin layer of the reactive material on the surface of said electrode, separating the anode and cathode with a diaphragm having its side facing the electrode which contacts the reactive material covered with a material covered with a material against which the reactive material is non-wetting, and passing an electric current between the anode and the cathode through the electrolyte to produce a compound of the reactive material and the product of electrolysis of the electrode in contact therewith.

2. The process of claim 1 wherein the nonwettable material is a glass fabric.

3. The process of claim 1 wherein the cathode is lead.

4. The process of claim 1 wherein the diaphragm is alundum.

5. The process of claim 1 wherein the nonwettable material is a synthetic organic plastic.

6. The process of claim 1 wherein the diaphragm is covered with a sleeve of nonwettable material.

7. A process for producing phosphine which comprises contacting anodic and cathodic electrodes with an electrolyte, the lower portion of the cathodic electrode being in contact with phosphorus, maintaining a thin layer of phosphorus on the surface of said cathode electrode, separating the anode and cathode with a diaphragm having its side facing the cathode covered with a material against which phosphorus is nonwetting, and passing an electric current between the anode and the cathode through the electrolyte to produce phosphine.

8. A process in accordance with claim 7 wherein said electrolyte is nonreactive with molten phosphorus, and is capable of forming hydrogen ions under the electrolysis conditions employed.

9. A process in accordance with claim 7 wherein the nonwettable material is a glass fabric.

10. A process for producing phosphine, which comprises contacting anodic and cathodic electrodes with an electrolyte, the lower portion of a cathodic electrode being in contact with phosphorus which is reactive with a product of electrolysis produced there, to produce phosphine, maintaining a thin layer of phosphorus on the surface of said electrode, separating the anode and cathode with a diaphragm having a side facing the cathodic electrode covered with a material selected from the group consisting of glass fabric, vinylidene polymers, polypropylene, polyurethane, chlorinated polyether, acrylonitrile resins, polyethylene, fluorinated hydrocarbon resins, polyester resins, polyvinyl chloride resins, graphite, phenolformaldehyde resins, natural gum rubber and chloroprene resins, against which the reactive material is nonwetting, and passing an electric current between the anode and the cathode through the electrolyte.
